UNITED STATES PATENT OFFICE.

JAMES A. BRENNAN, OF WORCESTER, MASSACHUSETTS.

ELECTRIC-ARC LAMP.

SPECIFICATION forming part of Letters Patent No. 664,209, dated December 18, 1900.

Application filed September 11, 1897. Serial No. 651,392. (No model.)

To all whom it may concern:

Be it known that I, JAMES A. BRENNAN, a citizen of the United States, residing at Worcester, in the county of Worcester and State of Massachusetts, have invented a new and useful Improvement in Arc-Lamps, of which the following is a specification, accompanied by drawings forming a part of the same, in which—

10 Figure 1 represents in front elevation an arc-lamp, a portion of the hood being broken away. Fig. 2 is an enlarged view of a portion of the feed-wire connected with the lower carbons and showing my improved feed-wire guard. Fig. 3 is a perspective view of the locking-plate carried by the lamp-chimneys and held against the board from which the lamp is suspended in order to maintain the lamp in a vertical position, the plate shown 15 in Fig. 3 being adapted for a double lamp; and Fig. 4 is a top view of a locking-plate designed for a single lamp and having a portion broken away to disclose one of the clamping-screws.

20 Similar letters refer to similar parts in the different figures.

My present invention relates to certain improvements in the class of electric lamps known as "arc-lamps;" and it has for its objects to provide a guard for the feed-wire throughout that section exposed either to the heat of the lamp or to the contact of the attendant in replacing the carbons by which the insulation of the feed-wire is liable to become impaired and also to provide means whereby the lamp can be maintained in a true vertical position and held from being swayed by the wind or other causes.

Referring to the drawings, Fig. 1 represents 25 in front elevation an arc-lamp supported upon a post A by means of the vertical rods B B, which sustain a horizontal board C, to which the hood D is attached and from which the lamp proper is suspended by means of metallic hooks E, attached to the board C and engaging hooks F, attached to the lamp, said hooks constituting a part of the circuit through which an electric current is supplied to the upper carbons.

30 G G denote the rod-tubes of the lamp, which in the present instance is represented as a double lamp or having two pairs of carbons

consisting of the upper carbons H H and the lower carbons I I. The lower carbons I I and globe J are suspended by rods K K, and the 35 lower carbons are supplied with an electric current through a feed-wire L, which is carried down in contact with the inner side of one of the rods K. The wire L consists of a metallic core covered with insulating material 40 N in the usual manner, and to that portion of the feed-wire which is most exposed to the heat of the lamp I apply a metal guard enclosing the insulating material and consisting of a closely-wound coil of wire forming a 45 flexible sleeve O, which is capable of being drawn on over the end of the feed-wire and brought into position to cover that portion subjected to the greatest heat or liable to be impaired by the attendant in replacing the 50 carbons. The sleeve O is wound upon an arbor of sufficient length to protect as much of the wire as needs protection and of the proper internal diameter to allow it to be slipped over the feed-wire, so it can readily 55 be applied to or removed from any lamp or a new one substituted.

I am aware that it is not new to wind a coil of wire around an electric cable to form an outside armor to prevent mechanical injuries 60 thereto, and I do not claim such; but my invention consists of a previously-wound coil forming a sleeve adapted to be slipped over the end of the feed-wire and adjusted in position to cover the portion of the feed-wire 65 needing protection. When placed in position, the sleeve O is capable of being bent to fit the side of the arm B, as at P P', and is held in position by a wire O, wound around the sleeve O and the arm B.

90 The device, as represented in the accompanying drawings, for locking the lamp in a vertical position consists of a locking-plate R, (represented in perspective view in Fig. 3,) comprising the two clamping-blocks R' 95 and R'', provided with holes R³ R³, fitting the rod-tubes G G, upon which the locking-plate is clamped by means of a tightening-screw S. The upper side of the locking-plate is preferably provided with rubber blocks T, 100 attached to the locking-plate and bearing against the under side of the board C, from which the lamp is suspended, in order to allow the lamp to yield slightly, the tension of

the rubber blocks T also serving to hold the hooks E and F in close contact, so as not to impair the circuit.

In Fig. 4 I have represented a locking-plate 5 U, provided with a single hole U', designed for a single lamp having but one rod-tube. The plate U is provided with the rubber blocks T and is clamped upon the chimney by two clamping-screws S S, one upon each 10 side of the chimney-opening U'. The clamping-screws S S engage nuts inserted in one of the clamping-blocks, one of said nuts being represented at V, Fig. 4. The locking-plate R is slipped down on the rod-tubes G to allow 15 the hooks E and F to be engaged when the locking-plate R is pushed upwardly against the under side of the board C and clamped in position by means of the clamping-screws S, with the rubber blocks T preferably slightly compressed and bearing 20 against the under side of the board C, thereby holding the lamp against upward movement, which would break the contact of the hooks E and F, and also holding the lamp from 25 being swayed by the wind or other causes.

In case a feed-wire is employed for the upper set of carbons the locking-plate R may be applied to the rod-tubes G above the board C and resting thereon either with or without 30 a locking-plate upon the under side of the board, as represented. Therefore I do not confine myself to the specific position of the locking-plate R or to the use of a single locking-plate on a lamp.

35 The essential feature of my locking device consists in the employment of a plate carried by the lamp and parallel with the horizontal board C or the hanger-board of the lamp, preferably with a yielding pressure between 40 the plate and the hanger-board, said yielding pressure tending to maintain the plate parallel with the board C, and thereby holding the lamp in a vertical position or restore the lamp in case it has been moved out of a 45 vertical position. For convenience I connect

the plate to the lamp by clamping it to the rod-tubes; but I do not confine myself to this method of supporting the locking-plate by the lamp.

It is customary in arc-lamps suspended 50 from the board C to provide an opening through the center of the board of considerable size to receive the rod-tubes G, and the space within the hood affords a secure and inviting place for birds to build their nests. 55 By clamping the locking-plate to the rod-tubes I am able to hold it sufficiently near the board C to close this opening and prevent the access of birds to the hood of the lamp.

What I claim as my invention, and desire 60 to secure by Letters Patent, is—

1. In an electric-arc lamp, the combination with the lamp-tubes and hanger-board, of a plate adjustably attached to the lamp-tubes and bearing against the hanger-board, where 65 by the lamp is held from swaying, substantially as described.

2. In an electric-arc lamp, the combination with the lamp-tubes and a hanger-board, of a plate adjustably attached to said tubes and 70 held parallel with the hanger-board and yielding blocks interposed between said plate and said hanger-board and in contact therewith, substantially as described.

3. In an electric-arc lamp, the combination 75 with the rod-tubes and hanger-board, of a locking-plate, means for adjustably attaching said locking-plate to the rod-tubes of the lamp, whereby it is held in a position parallel with the hanger-board, yielding cushions 80 interposed between said locking-plate and said hanger-board and means for supporting the lamp from said hanger-board, substantially as described.

Dated this 23d day of August, 1897.

JAMES A. BRENNAN.
